UNITED STATES PATENT OFFICE

2,202,352

CLOTHESPIN

Frank W. McGugin, Richmond, Calif.

Application March 1, 1939, Serial No. 259,254

2 Claims. (Cl. 24—137)

This invention relates to improvements in clothespins and has particular reference to a clothespin which may be locked to hold the clothes upon the line and prevent the wind from blowing the clothes from the line.

5 The principal object of the invention is to produce a clothespin of the character described that may be positively locked to prevent the clothes held thereby to be disengaged from the line.

10 A further object is to produce a clothespin of the class described that embodies in its construction a positive lock that will hold the handles of the device in locked relation.

15 Other objects and advantages will be apparent during the course of the following description.

In the accompanying drawing forming a part of this specification and in which like numerals are employed to designate like parts throughout 20 the same,

Fig. 1 is a side elevation of the improved clothespin, showing the locking or latching means in operative position;

Fig. 2 is an end elevation thereof;

25 Fig. 3 is a longitudinal sectional view taken on the line 3—3 of Fig. 2, and further disclosing the latch means of the clothespin.

Ordinarily, clothespins have been constructed which include a spring mechanism to close the 30 jaws thereof normally, but, to my knowledge, none have been produced which provide a positive locking or latching means to prevent the pin from being disengaged from the line.

In the accompanying drawing wherein for the 35 purpose of illustration is shown a preferred embodiment of my invention, the numeral 5 designates the pin in general, which comprises handles 6 and 7, pivoted at the point 8 and having line or clothes engaging tongs 9 and 10. Interposed between the handles 6 and 7 is a pawl 11, pivoted to the handle 7 at the point 12. This pawl extends across and between the handles 6 and 7 and is capable of engaging a plurality of struck-up members 13 formed in the handle 6. 40 The pawl 11 is additionally provided with a handle section 14 so that the pawl may be released from the struck-up members 13. It will be

noted that the pivot point 8 is provided with a spring 15, which spring normally encloses the pivot point and tends to exert pressure outwardly on the handles 6 and 7.

It will thus be seen that I have produced a clothespin which, when attached to a clothesline 5 and having the tongs 9 and 10 encompassing the clothes, will hold the same in tight and secure position upon the line.

It is to be understood that the form of my invention herewith shown and described is to be 10 taken as a preferred example of the same and that various changes relative to the material, size, shape and arrangement of parts may be resorted to without departing from the spirit of the invention or the scope of the subjoined claims. 15

Having thus described my invention, I claim:

1. A clothespin comprising a pair of elongated sheet metal members pivoted together adjacent one end forming gripping elements below the pivot, said members of a semi-circular form in 20 cross section above the gripping elements, a spring surrounding the pivot and having its ends in said semi-circular portions of the member, one of said members having notches struck inwardly within the semi-circular portion forming 25 ratchet teeth, and a pawl pivoted within the semi-circular portion of the other member and adapted to co-operate with the notches in the first mentioned member.

2. A clothespin comprising a pair of elongated sheet metal members pivoted together adjacent one end and forming gripping elements beyond the pivot, said members of a semi-circular form in cross section above the gripping elements, a spring surrounding the pivot and having its ends in said semi-circular portions of the members, one of said members having notches struck inwardly within the semi-circular portion forming downwardly extending ratchet teeth, a pawl pivoted within the semi-circular portion of the other member and adapted to co-operate with the notches in the first mentioned member, and a laterally extending operating handle carried by the pawl intermediate its ends and extending outwardly beyond the 40 elongated member. 45

FRANK W. McGUGIN.
